UNITED STATES PATENT OFFICE

2,415,820

SUPPORT FOR OFFICE APPLIANCES

Wayland F. Herring, Hammond, Ind.

Application March 16, 1945, Serial No. 583,149

1 Claim. (Cl. 248—23)

1

This invention relates to an adjustable support designed for supporting office appliances, such as typewriters, adding machines or the like, the primary object of the invention being to provide a support of this character which may be adjusted vertically for the particular requirement for the comfort of the user, thereby increasing the accuracy and efficiency of the operator of the appliance mounted thereon.

Another object of the invention is to provide a device of this character which will be exceptionally sensitive in operation, to the end that the movable supporting frame may be readily and easily raised or lowered, to a minute degree to insure the necessary adjustment for the convenience of the operator using the machine, mounted on the support.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawings:

Figure 1 is a plan view of an adjustable support constructed in accordance with the invention.

Figure 2 is a sectional view taken on line 2—2 of Fig. 1.

Figure 3 is a sectional view taken on line 3—3 of Fig. 4.

Figure 4 is an end elevational view of the device.

Figure 5 is a sectional view taken on line 5—5 of Fig. 4.

Figure 6 is a sectional view taken on line 6—6 of Fig. 4.

Referring to the drawings in detail, the device comprises a base section 5 and a vertically adjustable supporting section 6, connected with the base 5.

The base section comprises a length of angle bar material constructed to provide a rectangular frame, the angle bar being arranged so that one section thereof extends inwardly in a horizontal plane, providing a track 7 and a vertical guard flange 8.

Extending along the longitudinal sides of the base section, are angle bars 9 that have one of their flanges extended inwardly over the track 7 providing a guard rail for the rollers 10 that operate on the track. The angle bars 9 are secured

2

in position by means of the screws 11 that pass through registering openings in the angle bars 9 and the guard flange 8. The guard flange 8 prevents lateral movement of the rods 13, which rods provide supports for the rollers 10. These rods 13 have their inner ends disposed in sockets formed in the members 14 which are provided with transversely disposed threaded openings to accommodate the oppositely threaded portions 15 of the shafts 16, the inner ends of the shafts 16 being connected by means of the collar 17.

The shafts 16 are arranged in pairs and are disposed in spaced relation with respect to each other, adjacent to the ends of the support.

10 The vertically adjustable supporting section 6 of the device embodies a metal plate of a length and width convenient to accommodate a typewriter, adding machine or the like. The plate is indicated by the reference character 18 and is provided with an upstanding flange 19 formed along its longitudinal edges and one end thereof. Angle bars 20 are secured to the sides of the vertically adjustable supporting section and overlie the edges of the plate 18 as clearly shown by Fig. 25 of the drawings.

Secured to the lower surface of the plate 18 and disposed adjacent to the ends thereof, are bearings 21 arranged in pairs, each pair of bearings providing mounts for the shafts 22 that are disposed between the shafts 16 at each end of the plate.

Secured to the rods 13 are toggle members comprising connected plates 23 which plates are formed with bearings 24 that accommodate the shafts 22 so that the plates 23 may move with respect to the shafts 22. The plates 23 are arranged in pairs, and are so constructed that one plate of each pair is provided with a central cut-out portion to accommodate the tongue 25 of the cooperating connecting plate, so that transverse movement of the plate with respect to the shafts 22, will be prevented.

The shafts 16 have their outer ends extended through the end flanges of the base section 5 where they are supported in bearings 26 one end of one of the shafts being connected with the crank 27, by means of the pivot 28, so that rotary movement of the crank 27 will operate the shafts 16 to move the rods 13 of each pair of rods, towards or away from each other. It is obvious, when the rods 13 move towards each other, the upper ends of the connecting plates 23 will move upwardly, and when the rods 13 are spread apart, the upper ends of the plates 23 will be lowered resulting in the raising and lower-

ing of the vertically adjustable supporting section 6 to adjust the section 6 and typewriter or machine mounted thereon, so that the operator may conveniently operate the keys of the machine.

Because the crank 27 is pivotally connected with its shaft 16, it will be seen that the crank may be swung to the position shown in full lines in Fig. 3 of the drawings, and positioned under the clip 29, where it will be held out of the way.

What is claimed is:

An adjustable support comprising a rectangular base constructed of angle bar material, angle bars secured along the upper edges of the base and providing side channels with the base, shafts having oppositely disposed threads, extending through the longitudinal center of the base, a pair of transversely disposed rods, mounted at each end of the base, rollers on the ends of the rods, said rollers operating within the channels, socket members having threaded openings, mounted on the transversely disposed rods at points intermediate their ends, said shafts being threaded in said socket members, toggle members comprising wide plates connected with the transversely disposed rods, an upper supporting 25

member, transversely disposed shafts mounted on the supporting member and to which the upper edges of the toggle members are pivotally connected, and means for operating the shafts simultaneously, swinging the toggle members vertically, raising and lowering the upper supporting member in a true horizontal plane.
